UNITED STATES PATENT OFFICE.

EDMUND B WEDMORE, OF RUGBY, ENGLAND, ASSIGNOR TO GENERAL ELECTRIC COMPANY,
A CORPORATION OF NEW YORK.

ELECTRIC SWITCH.

No. 910,833.

Specification of Letters Patent.

Patented Jan. 19, 1909.

Application filed November 20, 1905. Serial No. 288,213.

To all whom it may concern:

Be it known that I, EDMUND B. WEDMORE, a subject of the King of Great Britain, residing at Rugby, England, have invented certain new and useful Improvements in Electric Switches, of which the following is a specification.

The present invention relates generally to electric switches of the oil break type and 10 more particularly to a device for readily placing the oil vessel in which the contacts are separated in position with reference to the other switch parts.

My invention is particularly applicable to 15 that type of oil switch now in common use in which both the fixed and movable contacts extend downwardly from a horizontal support, to the under side of which the oil vessel is secured when the switch is in condition for operation. In such a construction 20 the contacts are usually some distance from the floor and it is necessary to raise and lower the oil can some distance in attaching it to and removing it from its support.

25 In carrying out my invention I preferably employ a lifting lever frame which is provided with a swinging fulcrum at one end and at an intermediate point with suitable projections which engage sockets located on 30 opposite sides of the oil vessel. The outer end of the frame is provided with a handle which may be drawn upward to lift the oil can into its position about the switch contacts or may be lowered to lower the oil can 35 to the floor.

The character of the invention will be more fully understood upon reference to the following description taken in connection with the accompanying drawing in which the 40 preferred form of the invention is illustrated.

In said drawing, Figure 1 is a side elevation of a switch of well-known construction to which the lifting device of the present invention is shown applied; Fig. 2 is a view 45 illustrating the stirrups which provide the swinging fulcrum for the lifting frame; and Fig. 3 is a perspective view of the lifting frame detached from the switch.

Throughout these views like characters 50 refer to like parts.

The switch illustrated is of standard construction and comprises essentially a horizontal frame or support 10, fixed contacts 11 depending therefrom, movable bridging contacts 12 carried by a yoke 13, and lever

mechanism 14 by which the movable contacts are reciprocated in response to the movements of the operating lever 15.

The frame 10 is preferably a casting secured to the rear of the panel 16 or other like insulating support. The lever mechanism by which the yoke 13, and consequently the contacts 12 are reciprocated, comprises a bell-crank lever 17 pivoted at 18 to the rear end of the frame 10, and at the point 19 to the yoke 13. Another bell-crank lever 20 is pivoted at the forward end of the frame 10 at the point 21, and the rear end of this lever and the point 22 of the lever 17 are connected by a link 23. A suitable link 24 extending 70 through an aperture 25 in the panel 16 connects the bell-crank lever with the operating lever 15. An escutcheon plate 26 provided with a stop 27 for the operating lever is secured to the face of the panel 16 by bolts 28. 75 The fixed contacts 11, as well as the movable contacts 12, are adapted to be surrounded by the oil can 29 which is provided with an interior lining 30 and partitions 31 of wood or other suitable insulating material, as is well known in the art, the partitions 31 separating the different phases of the circuit, a three-phase switch being shown in the present instance. The oil can 29 is normally held up 80 against the under side of the frame 10 by latches 32 of any preferred form. The above switch construction, as previously stated, is of standard construction and constitutes no 85 part of the present invention.

In carrying out the present invention the 90 opposite sides of the oil can 29 are provided with plates or projections 33 formed so as to provide an inverted V-shaped socket. These 95 sockets are located, as clearly illustrated, near the upper part of the oil, above the center of gravity of the filled can, so that when the can is supported by them it will always remain in vertical position. The lifting frame 34 comprises substantially parallel 100 levers 35 which extend on opposite sides of the oil can 29 and are provided on their rear ends with hooks 36 which engage with a stirrup 37 hung upon the frame 10. The opposite ends of the levers 35 are connected by a lateral brace 38 and a handle 39. At 105 an intermediate point these levers are provided with upwardly-extending pins or projections 40 which are adapted in operation to enter the sockets formed by the plates 33.

As will be apparent from an inspection of 110

the drawing, when it is desired to remove the oil can 29, the lifting frame 34 may be put in place about the oil can with its levers 35 extending on opposite sides of the can and its ends hooked into the stirrup 37. It may then be lifted to the position illustrated in full lines in Fig. 1, thus seating the pins or projections 40 in the sockets formed by the plates 33. While held in this position the latches 32 may be manipulated to free the can which may then be readily lowered by gradually lowering the outer end of the frame 34. In replacing the oil can, this operation is reversed. However, in the latter case it will be noted that by reason of the swinging fulcrum formed by the stirrup 37 the can may be readily adjusted laterally into the right position to be engaged by the latches 32. In addition to the accuracy thus obtained in setting the oil can, the frame 34 is light and may be readily carried about from switch to switch, so that a single frame is sufficient for a large number of switches. The construction of the frame is also such that it occupies little space at the sides of the oil can and therefore can be used where a number of oil switches are located side by side in close proximity on a common switchboard.

30. What I claim as new and desire to secure by Letters Patent of the United States, is:

1. The combination of an electric switch, a detachable oil can for inclosing the switch contacts, and lever mechanism for shifting said oil can into and out of its inclosing position, said mechanism being detachably connected to its fulcrum.

2. The combination of an electric switch having downwardly-projecting contacts, a detachable oil can adapted to be moved upward around said contacts, and lever mechanism for raising and lowering said oil can into and out of said inclosing position said mechanism being detachably connected to its fulcrum.

3. The combination with an electric switch comprising a support for the switch contacts and a detachable oil can for inclosing said contacts, of means connected to said support for shifting the oil can vertically and laterally to bring it into and out of its inclosing position.

4. The combination with an electric switch comprising a support for the switch contacts and a detachable oil can for inclosing said contacts, of a lever for raising and lowering the oil can, and a fulcrum for said lever movably mounted on said support to permit lateral movement of said lever and oil can.

5. The combination of a support, switch contacts mounted beneath said support, a

detachable oil can for inclosing the switch contacts, means for securing said oil can to said support in its inclosing position, and independent means connected to said support for shifting said oil can vertically and laterally into and out of its inclosing position.

6. The combination with an electric switch comprising a support carrying downwardly projecting contacts, and an oil can adapted to be moved upward into position to inclose said contacts, of a lifting frame pivotally secured to said support and pivotally connected to said oil can at a point above its center of gravity.

7. The combination with an electric switch comprising a support for downwardly projecting switch contacts, and a detachable oil can movable upward into position to inclose said contacts, of lifting means for raising and lowering said oil can detachably pivoted to said support and connected to said can at a point above its center of gravity.

8. The combination with an electric switch comprising a support for the switch contacts and a detachable oil can for inclosing said contacts, of a lever for raising and lowering said can, and a swinging stirrup mounted on said support to constitute a movable fulcrum for said lever and permit lateral movement of said oil can.

9. The combination of an electric switch having downwardly-projecting contacts, an oil can adapted to be moved upward so as to inclose said contacts, a support, a lifting frame for raising and lowering said oil can pivotally secured to said support and pivotally supporting said oil can, and a swinging stirrup constituting a movable fulcrum for said frame whereby said oil can may be laterally shifted into its proper position.

10. The combination of an electric switch having downwardly-projecting contacts, an oil can adapted to be moved into position to inclose said contacts, a support to which said can may be secured when in said inclosing position, a swinging stirrup depending from said support, sockets on opposite sides of said oil can, a lifting frame comprising substantially parallel members carried at one end by said stirrup, stiffening members extending between said parallel members at the opposite end, and projections for engaging said sockets extending from intermediate points on said parallel members.

In witness whereof I have hereunto set my hand this sixth day of November, 1905.

E. B. WEDMORE.
